UNITED STATES PATENT OFFICE.

LEWIS C. VAN RIVER, OF DETROIT, MICHIGAN, ASSIGNOR, BY MESNE ASSIGNMENTS, TO
AERO MOTORS CORPORATION OF AMERICA, A CORPORATION OF DELAWARE.

INTERNAL-COMBUSTION ENGINE.

1,233,271.

Specification of Letters Patent. Patented Aug. 28, 1917.

Application filed May 15, 1916. Serial No. 97,624.

5. *to whom it may concern:*

Be it known that I, LEWIS C. VAN RIVER, a citizen of the United States, and a resident of Wayne county, city of Detroit, State of Michigan, have invented certain new and useful Improvements in Internal-Combustion Engines, of which the following is a specification, reference being had to the accompanying drawings.

10. This invention relates to improvements in internal combustion engines and may be applied to either the two cycle, four cycle or double acting type of explosive engines, although in the accompanying illustrations I have shown it in connection with a four cycle engine.

15. The object of this invention is to increase the efficiency by means of a new construction and arrangement of engine, wherein it is possible to greatly increase the compression of any explosive vapor, particularly such as gasoline or other products of petroleum, without danger of preignition.

20. By means of these improvements it is possible in this present engine to obtain almost any degree of compression desired without danger of preignition.

25. Other advantages obtained are, greater rapidity of expansion after combustion, mechanical agitation of the fuel vapor at the time of ignition, an increase in the leverage exerted by the piston upon the crank arm at the highest point of expansion after combustion and a more complete scavenging of the 30 products of combustion upon exhaust, the same being replaced by fresh air, explosive vapor or both in any pre-determined proportion.

35. This invention may be applied to any form or style of engine and may be adapted to those engines having cylinders and pistons rotating around an axis, as well as those wherein the cylinders are stationary.

40. Reference is made to the accompanying drawings in which:

Figure 1. is a longitudinal section of motor on line C—C of Fig. 3.

Fig. 2. is a transverse section on line A—A of Fig. 1.

45. Fig. 3. is an end view of engine looking in the direction of arrow "R" (Fig. 1).

Fig. 4. is a crank diagram beginning with suction stroke.

Fig. 5. is a diagrammatic view showing

position of valves at the end of suction stroke.

Fig. 6. is a crank diagram at end of suction stroke.

Fig. 7. is a diagrammatic view showing position of valves at the end of compression stroke.

Fig. 8. is a crank diagram at end of compression stroke.

Fig. 9. is a diagrammatic view showing position of valves at point of ignition.

Fig. 10. is a crank diagram at point of ignition.

Fig. 11. is a diagrammatic view showing position of valves at end of expansion stroke.

Fig. 12. is a crank diagram at end of expansion stroke.

Figs. 13 and 14 show different arrangements of engine wherein a plurality of two cylinder units, according to this invention, are employed.

Like letters and numerals of reference denote like parts in the various figures.

Piston C. of cylinder E. is connected by the usual connecting rod 1, to an arm 2, of the crank shaft 3, spaced in this instance 45 degrees, upon the crank shaft, from the crank arm 4, which carries the connecting rod 5, of piston D. operating in cylinder F. 6 is the fly wheel, 7 the sprocket gear that drives the chain 13 connected to the cam shaft 8, which operates the exhaust and intake valves 9, 9^a, 9^b, 9^c through the tappet rods 10, 10^a, 10^b, 10^c. Cam shaft 8 also operates the sleeve valve 11 by means of the sleeve connecting rod 12, operated by the crank pin 25 of the arm 28 of the cam shaft 8. The cam shaft is geared to the crank shaft 3, by chain 13, reducing its rotation in relation to the crank shaft in this instance 1 to 2. 14 is the usual cylinder wall, 15 the water jacket, and 16 the water jacket. The oil and water inlets and outlets are not shown in detail, but of course may be arranged in any well known manner. 17 is a spark plug, 18 the crank case, 19 the intake valve for cylinder F., 20 the intake valve for cylinder E., and 21—21 exhaust valves. 22—22 are piston rings placed between the head of cylinder E. and the sliding sleeve 11; 23 is an opening or port in the walls 14—14, connecting cylinder E. with cylinder F. and is opened and closed by the sliding sleeve 11 at intervals hereinafter.

explained. 24 is an opening or port in the sliding sleeve 11 to connect cylinder E. with cylinder F. at pre-determined intervals and the sliding sleeve 11 closes these cylinders 5 off from communicating with each other, also at pre-determined periods.

The operation of the engine is as follows:

Referring now to Fig. 1, when piston D. is at the top dead center of its exhaust stroke, 10 the inlet valve 9 opens and the inlet 19 is connected to a manifold leading from the carburetor in the usual manner, but the gas mixture in the carburetor (not shown), is kept at a much richer mixture than in ordinary use for combustion engines. For example, the mixture in this instance would be preferably about one part of gasoline vapor to four parts air, and as the piston D. descends on its suction stroke, this rich 15 mixture is drawn into the cylinder F.; the piston C. in cylinder E. follows at 45 degrees lag upon the crank shaft behind piston D., and therefore at the time piston D. begins its suction stroke, piston C. is just finishing its exhaust stroke, and the sliding sleeve 11 is moving upward and thus the opening 24 is moved out of the path of the port 23, closing off all communication between the two cylinders E. and F., as shown 20 in Fig. 4, and as the clearance space 26 of cylinder E. is very small, all of the exploded gases practically are eliminated from this cylinder through the exhaust valve 21. The clearance space in cylinder F. may be proportioned to give any desired compression of the fuel charge in cylinder F. On the suction stroke of piston C. in cylinder E., air from the atmosphere is drawn into the cylinder through the inlet valve 20. Therefore 25 cylinder E. at the end of the suction stroke, is entirely filled with fresh air, the products of the previous combustion having been entirely ejected on the exhaust stroke just completed.

40 In addition to this, during the exhaust stroke, the port 24 in the sliding sleeve 11 is in the path of the communicating passage 23 between cylinders E. and F., and thus admits a current of air through the clearance space 27 into cylinder F., thus aiding 45 to scavenge the burnt gases from cylinder F.

On the compression stroke which now follows, piston D. compresses the rich charge of gasoline vapor to desired point according 50 to the size of the clearance space 27 predetermined, and as the communicating port 23 between cylinders E. and F. is now closed by the sliding sleeve 11, as shown in Figs. 5 and 6, the contents of cylinder F. and cylinder E. are at the moment kept entirely 55 separate from each other and as the cylinder E. is preferably made larger than cylinder F. the amount of compression desired prior to ignition of the charge can be pre-determined. In this instance cylinder E. is pro-

portioned so as to give it about one and one-half times the volumetric capacity of cylinder F.; thus when piston D. reaches its upper dead center and for example, we will say that the gasoline vapor has been compressed to 90 lbs. per square inch in cylinder F.; piston C. is still 45 degrees early on crank shaft from its upper dead center and the clearance space in cylinder E. is very small (in this instance merely enough to 70 allow the valves to work freely) therefore at 45 degrees lag, from upper center the pressure in cylinder E slightly exceeds that in cylinder F. at the same instant, and at this point the sliding sleeve 75 11 begins to open the port 24 as shown in Figs. 7 and 8, and as the piston C. moves toward the upper dead center the port 24 opens very rapidly and admits the air under compression in cylinder E to rush 80 into the clearance space 27 of cylinder F. at a high velocity, thus thoroughly mixing the rich gasoline vapor previously admitted to the cylinder F. with highly compressed air. As the volumetric capacity of cylinder E. 85 is greater than that of cylinder F. the pressure rapidly increases in both cylinders as the piston C. moves toward the top of cylinder E. until piston C. is very near the upper center, so that, for illustration, in 90 the proportion shown in the accompanying figures, when piston C. is within say 22 $\frac{1}{2}$ degrees of the upper center and piston D. 95 22 $\frac{1}{2}$ over the center, the compression in both cylinders has reached its maximum, say for example, 200 lbs. per square inch, but this increase has taken place almost instantly in cylinder F. where the gasoline vapor is still confined, the high pressure having occurred or rather having been forced into cylinder F. 100 between the time that piston C. was moving from a point 45 degrees lag to 22 $\frac{1}{2}$ degrees lag from upper center. 105

At about this point the ignition through the spark plug 17 should take place and 110 because of the thorough mixing of the explosive product, due to the rapid influx of compressed air at this instant, combustion occurs almost instantaneously and is complete at about the time that piston C. reaches 115 its upper dead center, and piston D. at this point will be 45 degrees over its upper dead center, thus giving the explosive charge greater leverage upon the crank arm 4, and consequently increasing the rate of expansion for the next 45 degrees travel about three times what it would amount to if the charge were exploded when piston was on the dead center as is the usual custom in engines now in general use. Because of the 120 greater volumetric capacity of cylinder E. the pressure in both cylinders will remain at practically its maximum from the time piston C. is at 22 $\frac{1}{2}$ degrees lag until it reaches the upper center; thus both ignition and 125 130

complete combustion occur at the highest point of compression and after piston D. is more than 20 degrees past the dead center.

The port 24 in the sliding sleeve 11 now 5 remains open, as shown in Figs. 9, 10, 11 and 12, during the entire expansion and exhaust strokes, and the exploded vapor from cylinder F. rushes into cylinder E. and acts upon the piston C. at the same 10 time it is acting upon piston D., a still further increasing the rapidity of expansion and applying the force exerted by the high pressure due to combustion to the accomplishment of useful work in both cylinders. 15 Thus a larger degree of heat is taken off in useful work instead of being used up in radiation through the cylinder walls as is now done in general practice where the combustion is completed at or near the dead 20 center of the compression stroke.

The exhaust valves in both cylinders are timed to open when the piston D. reaches a point near its lower dead center after which the exhaust stroke drives the burnt 25 gases out in the usual manner, excepting that the reciprocating action of the cylinders C. and D. have a tendency to clear the compression space 27 of cylinder F. of the burnt gases because of the volumetric pressure exerted by piston C., which is larger 30 in circumference than piston D., and the further advantage that the clearance space in cylinder E. is so small that all of the burnt gases are ejected therefrom before 35 the suction stroke begins.

It is a well known fact that upon the combustion of vapor in an inclosed chamber the pressure therein increases from three to 40 five times what it was before explosion (depending somewhat upon the mixture and the rapidity of combustion) so that if the pressure be raised before ignition the thermal efficiency of the fuel is increased in proportion to the increase of compression.

45 It will thus be seen that much higher compression is obtained without danger from preignition, because in the first place the mixture in the cylinder F. (or explosion cylinder) is too rich to ignite readily until 50 after the air mixes with it, but even aside from this, the pressure obtained by piston D. need not be sufficiently high to cause preignition and as the high compression occurs almost instantly, *i. e.*, during the period that 55 piston C. travels 22 $\frac{1}{2}$ degrees on the crank shaft in the pressure cylinder E. practically simultaneously with the ignition by electric spark, no time is given here for preignition. It is also desirable and advantageous to have 60 combustion of the mixture completed as quickly as possible after ignition, so that even if the vapor does ignite spontaneously after the port 24 opens it will merely aid combustion, doing no harm whatever be- 65 cause such ignition will take place simul-

taneously with the firing from the electric spark. Ignition should be timed to occur so that piston C. will just about reach its upper dead center when combustion is entirely completed, thus both ignition and combustion occur at the maximum point of pressure and at the most advantageous time, while the vapor is being highly agitated through the movement of piston C. in the pressure cylinder E. so that a premature 70 explosion becomes an impossibility, as the explosion cannot occur too soon after the mixture becomes complete and compression is at its highest point.

In explosive engines now in general use, 80 the loss of power from the crank arm dead center reaches its maximum because as is well known the highest pressure from the explosion of vapor occurs at the instant of complete combustion and falls very rapidly 85 thereafter, so that during the first 45 degrees turning movement of the crank shaft immediately succeeding the piston reaching its upper dead center, the explosive pressure will have lost approximately one-third of 90 its initial force, and the piston will have traveled only about one-third of the distance vertically that it travels during the next or succeeding 45 degrees as in this instance when combustion is timed to occur at 45 de- 95 grees over the center.

It will be apparent that the same principle can be applied to an engine operating on the two cycle plan with such variations in the inlet and exhaust ports as might be necessary.

In the specification and claims I have used the word "lag" in connection with the piston which follows last or is behind the other on the crank arm and the term "lead" 105 in referring to the piston which first reaches the dead center on each stroke. I have also employed the term "pressure cylinder" for the cylinder E. or the one which draws in and compresses air or vapor to the highest 110 point, and "explosion cylinder" for cylinder F. or the one in which the explosion occurs.

While I have shown herein one of the cylinders as drawing in and compressing air only, it is to be understood that any vapor 115 or mixture might be drawn in in place of air, and that any other explosive vapor from those commonly called petroleum products may be used.

While I have described herein a sleeve 120 valve operating in cylinder E., it is to be understood that any other form of valve well known to the art might be employed to perform the functions herein described and it is distinctly understood that I do not limit myself to the construction of engine herein shown as any well known form of construction might be employed.

The radial distance between the crank arms may also be varied to suit conditions.

While I have shown two cylinders acting together, it is to be understood that any plurality of two may be used in any well known combination of engine, or that a single pressure cylinder might be applied to one or more explosion cylinders.

Having now fully described my invention, what I claim is:

1. In a combustion engine, the combination of two communicating cylinders one of which is larger than the other, means for closing the communicating passage between said cylinders at pre-determined intervals, a piston in each of said cylinders, a crank shaft operating said pistons, the piston in the smaller cylinder being given a fixed lead on said crank shaft with regard to the other and the clearance space being larger in the cylinder in which the piston is given the lead than in cylinder in which the piston is given the lag.
2. In a combustion engine, the combination of a common crank shaft and two pistons in communicating cylinders one of which is larger than the other, means for closing said communicating passage between said cylinders at pre-determined intervals, the piston in the smaller cylinder being given a lead in said crank shaft over the other piston so that the piston having the lead will reach its highest point of compression in cylinder after having passed the dead center on the compression stroke by at least 10 degrees of turning movement of crank shaft.
3. In a combustion engine composed of a pair of cylinders one cylinder being larger than the other and pistons operating upon one common crank shaft wherein the cylinders of each pair are inter-communicating and the piston operating in the smaller cylinder is connected in such manner to a crank arm of crank shaft in the lead of the piston operating in the other cylinder, as to cause the explosive vapor in one cylinder to reach its highest point of compression after its piston has passed the dead center of crank on its compression stroke by not less than 10 degrees radiating from the center of crank shaft, and means for interrupting the communication between said cylinders at predetermined intervals.
4. In a combustion engine, the combination of two inter-communicating cylinders of different sizes separated by a slidable sleeve at pre-determined intervals, each with pistons therein, means for admitting explosive vapor into one of said cylinders means for igniting the same, said pistons connected to a common crank shaft in such relation to each other that the expansion of vapor after same has been ignited is more rapid therein than when vapor is exploded in a single cylinder prior to its working stroke.
5. In a combustion engine, the combination of two communicating cylinders of

different sizes separated by a slidable sleeve at pre-determined intervals, means for admitting explosive vapor into one of said cylinders, a piston in each of said cylinders, both pistons connected to a common crank shaft, means for exploding a charge of compressed vapor within the smaller cylinder after the piston within said smaller cylinder has passed the dead center on the compression stroke by at least 10 degrees movement of the crank shaft and about at the same time that the other piston of the pair has reached the dead center on said compression stroke.

6. In a combustion engine, the combination of two communicating cylinders of different sizes separated by a slidable sleeve at pre-determined intervals, a piston in each of said cylinders, both pistons connected to a common crank shaft the piston operating in the smaller cylinder being given an advance upon said crank-shaft, means for admitting explosive vapor into one of said cylinders, means for igniting the same, means for expelling the exploded products from said cylinders and means for admitting fresh air into said cylinders.

7. In a combustion engine, the combination of a cylindrical unit composed of two inter-communicating cylinders separated by a slidable sleeve at pre-determined intervals, a piston in each of said cylinders, both connected to a common crank shaft, one in lead of the other of between 10 and 80 degrees, the cylinder within which the piston is given a lag of each unit being of greater volumetric capacity than the other, an air valve communicating with said first named cylinder and said cylinder having the greatest volumetric capacity having less clearance space than the other cylinder.

8. In a combustion engine composed of a pair of communicating cylinders of different volumetric capacities separated by a valve at pre-determined intervals, means for admitting an explosive mixture into one of said cylinders, a pair of pistons, and a common crank shaft so constructed and connected to both of said pistons that means are provided for causing said explosive mixture in said cylinder to be compressed to the highest point of compression obtainable on the compression stroke of said pistons at a pre-determined period after one of said pistons has passed the dead center on its compression stroke by at least 10 degrees and before the other piston has reached the dead center on said compression stroke.

9. In a combustion engine, the combination of two cylinders of different volumetric capacities communicating at one end, a valve closing said communication at pre-determined intervals, a piston in each of said cylinders, a crank shaft operating said pistons, the piston operating in the cyl-

- inder of smallest volumetric capacity being given a sufficient lead on said crank shaft with regard to the other piston to cause the vapor in said cylinders to reach its highest 5 point of compression after one of said pistons has passed the dead center of crank arm on its compression stroke by not less than ten degrees movement of said crank shaft.
10. In a combustion engine composed of a two cylinder unit of different sizes, each cylinder having a piston working therein, a communicating passage between the cylinders of each unit, means for closing said 15 passage at pre-determined intervals, means for admitting vapor to each of said cylinders, means for compressing the same, means for quickly transferring the vapor from the larger cylinder into the other during the compression period of one cylinder 20 and means for igniting the same.
11. In a combustion engine the combination of an explosion cylinder and a pressure cylinder, said pressure cylinder having 25 a larger volumetric capacity than the explosion cylinder, a piston in each of said cylinders connected to a common crank shaft, means for admitting vapor into each of said cylinders, means for quickly transferring 30 the vapor from the larger cylinder into the other during its highest point of compression and means for igniting the same.
12. In a combustion engine the combination of a pressure cylinder and an explosion 35 cylinder, the pressure cylinder having a larger volumetric capacity than the explosion cylinder, means for admitting vapor into each of said cylinders, means for compressing the same, means for quickly trans- 40 ferring the vapor from the pressure cylinder into the explosion cylinder in such volume as to raise the pressure within the explosion cylinder after the compression within said explosion cylinder has been completed and 45 means for igniting the same.
13. In an explosive engine, the combination of an explosion cylinder and a pressure cylinder larger than said explosion cylinder, a piston working in each of said cylinders both of 50 said pistons connected to a common crank shaft, the piston working within the explosion cylinder having an advance over the other of from ten to ninety degrees upon said crank shaft, means for admitting vapor 55 into both of said cylinders, means for quickly transferring the vapor from the pressure cylinder into the other at or near the end of the compression stroke in pressure cylinder and after the piston in explosion cylinder has passed the upper dead center, and means for igniting the same.
14. In an explosive engine, the combination of an engine composed of a two cylinder unit comprising an explosion cylinder 60 and a pressure cylinder having a greater 65
- volumetric capacity than said explosion cylinder, a piston working in each of said cylinders, both pistons connected to a common crank shaft, the piston operating in the explosion cylinder being connected to said crank shaft so that it will have a lead over the piston operating in the pressure cylinder, means for admitting vapor from the pressure cylinder into the explosion cylinder at pre-determined intervals, means for 70 admitting vapor from the explosion cylinder into the pressure cylinder at predetermined intervals and means for exploding vapor in the explosion cylinder.
15. In an explosive engine the combination of a plurality of cylinders of different sizes, communicating means between said cylinders, means for closing off said communicating means at pre-determined periods, a piston operating in each of said cylinders, 75 the piston operating in the smaller cylinder being given a lead upon the crank-shaft of the piston operating in the larger cylinder, means for admitting vapor into each of said cylinders independent of the other, the larger cylinder having a smaller clearance space than the smaller cylinder for compressing said vapor in one cylinder to a higher point of compression than in the other, means for quickly admitting the 80 highly compressed vapor from one cylinder into the other cylinder after the piston in said last mentioned cylinder has passed its upper dead center, to raise the pressure in said last mentioned cylinder to a higher 85 point than before said vapor was admitted and means for igniting the same.
16. The method of increasing the efficiency of explosive engines which consists in admitting an explosive vapor into an engine cylinder and compressing the same and when the piston in the engine cylinder has about reached its upper dead center, quickly injecting therein a large volume of highly compressed vapor so that the pressure in 90 said engine cylinder will be raised to a higher point after said piston has passed the center than was reached on its compression stroke, then during the admission of vapor igniting the vapor so that ignition and combustion will both occur during about the maximum pressure.
17. The method of increasing the efficiency of explosive engines which consists in first admitting a very rich explosive vapor into the engine cylinder, then compressing the same in the usual way, then at about its highest point of compression quickly admitting into said engine cylinder a non-explosive mixture at a higher pressure than 100 that attained by the explosive vapor, to thoroughly agitate the explosive vapor and mix with the same, thus raising the pressure in the engine cylinder after the piston therein has passed its upper dead center,

then igniting the vapor during the admission of the non-explosive vapor and at about the time that the pressure in the cylinder has reached its maximum highest point.

5 18. The method of increasing the efficiency of explosive engines which consists in admitting into the engine cylinder gasoline or other vapor so rich as to be non-explosive or not readily explosive from compression, 10 then compressing the same to any predetermined degree of compression in the usual way in the engine cylinder, then quickly injecting into said engine cylinder a very lean mixture of gasoline or other vapor, so 15 lean as to be non-explosive, but compressed to a higher degree of compression than that in the engine cylinder after the piston in said engine cylinder has reached its dead center, thus raising the pressure in the engine cylinder, causing a thorough agitation of the vapor therein which is instantly 20 mixed with the thinner injected vapor, thus forming a highly explosive mixture and igniting the same at about the highest point 25 of compression during the admission of vapor.

19. In a combustion engine, the combination of a pressure cylinder and an explosion cylinder, said pressure cylinder being of 30 greater volumetric capacity than the explosion cylinder, a communicating passage between the pressure cylinder and the explosion cylinder, a movable sleeve in the pressure cylinder, means for moving said sleeve 35 to close the communicating passage between the two cylinders at predetermined intervals, a piston in each of said cylinders connected to a common crank shaft, the piston in the explosion cylinder being given a lead 40 upon the crank shaft over the other piston, means for admitting vapor into each of said cylinders and means for igniting the same in the explosion cylinder.

20. The method of operating a combustion engine which consists in compressing a 45 rich charge in a cylinder and a lean charge in an adjacent cylinder of greater volumetric capacity than said first mentioned cylinder, by pistons operating therein in 50 such manner that the compression of the rich charge is completed before that of the lean charge, and then forcing said lean charge into the cylinder containing the rich charge, mixing with said rich charge and 55 raising the compression therein after its working stroke has begun, then during admission of the lean charge igniting the mixture.

21. The method of operating a combustion engine which consists in compressing a 60 rich charge in a cylinder and a lean charge in an adjacent cylinder of greater volumetric capacity than said first mentioned cylinder, by pistons operating therein in 65 such manner that the compression of the rich charge is completed before that of the lean charge, and then forcing said lean charge into the cylinder containing the rich charge, mixing with said rich charge and raising the compression therein after its 70 working stroke has begun, then during admission of the lean charge igniting the mixture and allowing the mixture after combustion to expand in both cylinders.

22. The method of operating a combustion engine, which consists in compressing in separate cylinders a rich charge and a lean charge by pistons operating therein in such a manner that the compression of the rich charge is completed before that of the 80 lean charge, in forcing said lean charge into the cylinder containing the rich charge and mixing the same with said rich charge after the working stroke in said cylinder has begun, in increasing the compression in said 85 cylinder during the first part of the working stroke and in igniting the charge in said last mentioned cylinder during the admission of said lean charge.

23. In a combustion engine, the combination with an explosion cylinder, of a pressure cylinder communicating therewith, said pressure cylinder having a larger volumetric capacity than said explosion cylinder, a 90 crank shaft and a piston in each of said 95 cylinders connected to said crank shaft, the piston in said explosion cylinder having a lead over the piston in said pressure cylinder.

24. In a combustion engine, the combination with an explosion cylinder, of a pressure cylinder communicating therewith, said pressure cylinder having a larger volumetric capacity than said explosion cylinder, means for admitting a lean charge to said pressure 100 cylinder, and a rich charge to said explosion cylinder, means for compressing said charges in their respective cylinders and for forcing the compressed lean charge into the explosion cylinder after its working stroke has 105 begun, and means for igniting the combined charge in said explosion cylinder.
